BY George Cook,
ATTORNEY.

UNITED STATES PATENT OFFICE.

SIGMUND STERNAU, OF NEW YORK, N. Y.

DESIGN FOR A STAND FOR CHAFING-DISHES.

SPECIFICATION forming part of Design No. 23,769, dated November 6, 1894.

Application filed October 6, 1894. Serial No. 525,177. Term of patent 3½ years.

To all whom it may concern:

Be it known that I, SIGMUND STERNAU, a citizen of the United States, residing in New York, county of New York, and State of New York, have invented and produced a new and original Design for Stands for Chafing-Dishes, of which the following is a specification, reference being had to the accompanying drawing, which shows the stand in perspective.

5 The leading or characteristic feature of my design is the open work scroll like legs, connecting the upper large ring and the lower smaller ring.

10 A represents the legs curved in the direc-

tion of their length, and of the skeleton scroll 15 like form as shown.

B represents the upper larger plain ring and C the smaller ornamented ring, the latter being attached to or connected with the legs or standards A by means of the foliated 20 brackets D.

What I claim is—

The design for a stand for chafing-dishes as hereinabove shown and described.

SIGMUND STERNAU.
